UNITED STATES PATENT OFFICE.

JOHN BOYLSTON, OF CHICAGO, ILLINOIS.

PUMP-REGULATOR.

SPECIFICATION forming part of Letters Patent No. 626,217, dated June 6, 1899.

Application filed November 7, 1898. Serial No. 696,776. (No model.)

To all whom it may concern:

Be it known that I, JOHN BOYLSTON, a citizen of the United States, residing at Chicago, in the county of Cook and State of Illinois, have invented certain new and useful Improvements in Pump-Regulators, which are fully set forth in the following specification, reference being had to the accompanying drawings, forming a part hereof, and in

which—

Figure 1 shows my said new device in side elevation. Fig. 2 shows a transverse section of the upper part of the diaphragm-chamber.

Like letters of reference denote like parts.
15 The object of my invention is to produce a simple, efficient, and very sensitive valve-regulator for pumping-engines and like service, adapted to be set to any desired point or desired capacity and from which it may be
20 varied by a very quick and slight adjustment of my said mechanism. To attain said desirable ends, I construct my said new device in substantially the following manner, namely:
25 To any balanced steam-valve α , (here represented by its chamber a ,) having a stem g , I attach a lever l , fulcrumed at f , of which its longer arm is suitably weighted, as with weights B or any equivalent mechanism and so near said fulcrum as to make the distance
30 between the parts f and g a long arm of a lever, and thus giving both ends of the lever l the same functions relatively, one relating to the weight and the other to the valve in a , by attaching an adjustable connecting mechanism, consisting of two rods h and h' , whereof one is provided with a right-hand thread and the other with a left-hand thread. An internally-threaded sleeve i receives and adjusts the ends of said rods by means of a hand-wheel C , forming a part of said sleeve. Said threaded rods are articulated to levers k and l , as shown, whereof the lever k is fulcrumed on a bolt e' in a fork on the cap-piece of the diaphragm-chamber c , and near said bolt e'
45 is received the actuating force or weight at e to the lever k , which is at the end of a stud centered in a disk j , resting on a diaphragm d in a chamber c . Said diaphragm is held between the flanges of said chamber and is
50 acted upon by fluid-pressure received through a pipe n , which discharges into and fills said chamber (indicated by the broken lines) be-

low the diaphragm. The upward pressure of the fluid in said chamber raises said diaphragm, and with it rises the disk j , exerting 55 its lifting force on the disk-stem at e , which in turn raises the lever k , and with it the connecting mechanism h h' at the long arm of the lever k , connected to the lever l near its fulcrum f of the lever l , whereby through 60 the motion of said connected mechanism the valve in the chamber a is closed in proportion to such motion. The regulable screw-stud m holds the lever k from moving below a fixed point, and through said connection the lever 65 l is also held to said adjustment. When the normal position of the lever k is established through said bolt, the hand-wheel C is turned until the desired amount of steam is obtained to work the pump. From what has been said 70 it is evident that whenever the force on the diaphragm is increased enough to overcome the weight B the valve-stem g will be moved to close its valve; also, that whenever a suddenly-increased demand for water comes it 75 can be supplied by simply turning the hand-wheel C so as to lower the weight B , and thus open the steam-valve at the other end of the lever l until the desired volume of water is obtained. By this arrangement of my levers 80 a very slight motion of the diaphragm will be sufficient to give a large travel to the valve and that at the same time the levers may be made quite light and short and the weight for the lever comparatively small, yet producing 85 a very efficient and cheap mechanism. To the pipe n , which leads from a water-tank or like reservoir, is attached a valve o for cutting off that source of force when necessary, and between said valve and diaphragm d is 90 attached an air-chamber p , with axially-opposed cocks q and r to provide a replenishable air-cushion and to relieve all shock or chattering of the governor and its connected mechanism.

95 Both levers k and l are to each other levers of the third order, and relative to the valve and weight the valve-lever is also twice a lever of the first order—once to the valve and once to the weight—and a lever of the third order relative to the power derived from the lever k .

100 What I claim is—

The combination with a reciprocable dia-

phragm and a regulator-valve, of an end-fulcrummed and adjustably-stopped lever, actuated by said diaphragm near said fulcrum, and a lever, fulcrummed between its ends, 5 whereof the shorter end is attached to said valve and the longer end weighted, said levers connected by oppositely-threaded rods in a sleeve provided with a hand-wheel, one

of said rods connected to the outer end of said diaphragm-lever and the other end thereof connected to the valve-lever near its fulcrum, substantially as specified.

JOHN BOYLSTON.
